SPRING DRAWHEAD AND BUFFER

Robert C. Kepner, Bloomsburg, Pa., assignor to
American Car and Foundry Company, New
York, N. Y., a corporation of New Jersey

Application July 18, 1938, Serial No. 219,734

12 Claims. (Cl. 213—9)

This invention relates to improvements in drawheads and buffers in general and in particular to such devices intended for use on mine or other industrial cars.

Previously constructed buffing and draft devices for mine and industrial cars have been quite expensive and hard to repair in most cases with the result that the majority of cars of this type are still being built with wood or other cushioning blocks, which are not satisfactory. It is an object, therefore of the present invention to provide a combined draft and buffer device which is inexpensive, simple and easily repaired.

A further object of the invention is the provision of a combined draft and buffer device which may be fully assembled as a unit exterior of the car and then quickly attached to the car or readily removed for repair.

A still further object of the invention is the provision of a bumper element which transmits both the buffing and draft forces to springs through suitable followers carried by the bumper itself.

A still further object of the invention is the provision of a buffer device in which the buffer or bump receiving face is strengthened during such times as it is resisting the buffing forces.

These and other objects of the invention will be apparent to persons skilled in the art from a study of the following description and accompanying drawing, in which:

Figure 1 is a plan view of the improved device with portions broken away to more clearly disclose the interior construction;

Fig. 2 is an end view of the device with portions broken away to disclose the interior construction;

Fig. 3 is a sectional view taken substantially on line 3—3 of Figure 1, and

Fig. 4 is a sectional view taken substantially on line 4—4 of Figure 1.

Referring now to the drawing in detail, it will be seen that the mechanism has been illustrated as applied to a car having an end housing A in which the preassembled buffing and draft device B is slidably mounted. The end housing is formed in the present instance of two plates, the upper of which is bent to substantially Z-form having a long upper flange 2, web 4 and short lower flange 6, while the lower plate 8 is substantially flat and is adapted to be secured to the short flange of the upper member by any suitable means such as rivets 10. In the present instance the end of the car floor 12 is interposed between the upper and lower plates, while the

5 sides thereof are attached in any suitable manner to the side sills 14 which in the present instance are of inverted bulb angle form. The upper or Z-formed portion of the housing has the top flange extended as at 16 to overlap the flange of the side sill for attachment thereto by any suitable means, such as 18, while the lower plate is securely attached to the web of the sills by angle means 20. It will thus be seen that an extremely rigid housing is formed which may be easily attached to the car structure leaving an open pocket facing outwardly of the car for reception of the combined buffing and draft device later to be described. In case a rigid end wall is desired, this may be attached to the end housing by means of angle 22 welded or otherwise secured to the top flange of the upper housing member. The web of the upper housing member is braced and stiffened by means of buttressing gussets 24

15 welded or otherwise secured to the web and short flange immediately behind the most heavily stressed sections. In forming the upper member of the end housing the outer central portion of the flange 2 is removed as at 26 in order to receive a draft member later to be referred to and is also pierced on either side thereof as at 28 to receive bolts later to be referred to and which are adapted to extend into holes 30 pierced in the lower plate.

20 The combined buffer and draft device itself consists of a bumper element having an upper flange 32 and lower flange 34 extending rearwardly from a connecting web or buffing face 36 curved to any desired radius. The upper and lower flanges are of considerable depth and are provided adjacent their rear edges with follower lugs 38 of substantially U-form having the legs 40 extending forwardly toward the buffing face. These follower lugs are securely welded or otherwise fastened to the rear portion of the bumper flanges in such a position as to receive therebetween back stop blocks 42 secured to the web of the end housing by any suitable means such as countersunk rivets 44. In order to reinforce the buffing face and transfer buffing forces to the springs a reinforcing and stiffening plate 46 is provided having its front portion curved in conformity with the buffing face, while its rear portion is welded or otherwise secured to front followers 48 carrying on their rear faces short sections of tubing welded thereto to form spring centering lugs 50. The rear portion of the stiffening plate is slotted as at 52 in order that it may move inward relative to bolts 54 extending through the holes 28 and 30 of the top and bot-

tom housing plates. These bolts will prevent outward movement of the front followers and the attached reinforcing and bump transferring plate. It will be necessary, of course, in order to permit inward and outward motion of the bumper for slots 55 to be cut in the top and bottom flanges as clearly shown in Fig. 3. In some instances where the bumping strains will be excessive blocks may be welded to the top and bottom flanges of the bumper on either side of the slots and ahead of the front followers, thus causing the top and bottom bumper flanges to transfer strains to the front follower and assist the stiffening plate. In order to provide increased bearing area for coupling pin 56 a plate 58 is welded to the central portion of the top bumper flange immediately ahead of angular coupler bar 60 which has its rear portion extending through the top flange of the bumper to which it is fastened. The coupler bar reinforcing plate and top and bottom flanges of the bumper have openings therein adapted to receive the coupling pin, while the stiffening plate has a slot 62 formed therein in order that the coupling pin may move outward relative thereto. It is to be noted that the reinforcing plate 58 and coupler bar 60 are of such width as to fit between the sides of slot 26 in the top flange of the end portion, thus not only providing draft portions but guiding the bumper element and relieving the bolts 54 of any material side shear which they otherwise might receive from angular buffing strains. In order to resiliently absorb the buffing and draft shocks springs 64 are provided having their front ends bearing against the front follower plates, while their rear ends bear against rear follower plates 68 adapted to have bearing on follower lugs and back stop blocks. The springs are maintained in proper relation upon the back followers by suitable centering means such as a section of tubing 70 welded or otherwise secured to the rear followers.

The combined bumper and draft unit may be readily assembled by inserting the stiffener plate with its attached front followers into the bumper member, after which the springs are placed in position and put under sufficient compression to permit insertion of the rear followers 68 ahead of the follower lugs which have been welded to the flanges of the bumper cap. It is, of course, obvious that if under certain conditions this compression necessary for assembly is excessive, the outer ears or legs 40 of the follower lugs may be made removable and attached after the insertion of the rear followers. The unit may also be assembled of course, by welding the follower lugs in position as a final step in the assembly operation. As soon as the unit is assembled then the entire unit may be bodily inserted into the end housing and bolts 54 dropped into position retaining the unit in the end housing.

The operation of the improved device is as follows: Assuming a bumping force be imparted to the bumping face, this force will be transferred through stiffening plate 46 to the front followers 48, thence through the springs to the rear followers 68 which are held against inward movement by the stop blocks 42. During this inward movement of the bumper cap and reinforcing plate the follower lugs 38 will move away from the rear followers, while the reinforcing plate 54 will move inward relative to the fixed bolts 54 with the inward movement of the coupling pin and coupler bar being permitted due to the slots formed in the upper and lower housing plates

as well as in the stiffening plate. Upon application of a draft force to the coupling pin the entire bumper cap assembly will move outward with the draft strain being transferred through the bumper flanges to the follower lugs, thence through back followers 68 and springs 64 to the front followers 48 which are held in position by means of the bolts 54 extending through the top and bottom members of the end housing. During the outward motion of the bumper the bumper cap will move away from the stiffening plate and such movement is permitted by the slot 62 in the stiffening plate. It will thus be seen that a unit has been provided which may be preassembled and quickly attached to the car or removed therefrom and that if any parts are damaged they may be easily replaced or repaired without in any way affecting the other parts of the unit. It should also be noted that the stiffening plate will back up the bumping face of the bumper during such times as buffer forces are being received, thereby lessening the possibility of damage being done to the buffing face.

While the improved device has been described more or less in detail, it is obvious that various modifications, rearrangements of parts and changes in manner of assembly will be apparent to persons after a study of the construction and all such modifications, rearrangements of parts and changes in assembly are contemplated as fall within the scope of the following claims.

What is claimed is:

1. A spring bumper for a vehicle comprising in combination, a transverse housing secured to the vehicle and having an opening directed outward the end of the vehicle, a bumper member slidable longitudinally of the vehicle and enclosed in part by said housing, resilient means resisting the longitudinal sliding of the bumper member, and bumper reinforcing means extending laterally substantially the width of said bumper and stiffening substantially the entire central portion thereof and transferring buffing shocks therefrom to said resilient means, said bumper reinforcing means being free of attachment to said bumper and effective only during application of buffing forces.

2. A spring bumper for a vehicle comprising in combination, a transverse housing secured to the vehicle and having an opening directed outward toward the end of the vehicle, a bumper member consisting of a vertically disposed buffing face and rearwardly directed flanges, said bumper flanges extending into said housing and being slidable longitudinally thereof, resilient means opposing the longitudinal sliding of the bumper member, and bumper reinforcing means extending laterally substantially the width of said bumper substantially parallel to said flanges and stiffening the buffing face intermediate said flanges and transferring buffing shocks from the buffing face to said resilient means, said bumper reinforcing means being free of attachment to said bumper and effective only during application of buffing forces.

3. A spring bumper and draft device for a vehicle comprising in combination, a transverse housing secured to the vehicle and having an opening directed outward toward the end of the vehicle, a combined bumper and draft member slidable longitudinally of the vehicle and enclosed in part by said housing, said member consisting in part of a buffing face and rearwardly directed flanges, at least one of which is provided with coupler receiving means, resilient means resist-

ing the longitudinal sliding of the bumper member, bumper reinforcing means extending laterally substantially the width of said bumper substantially parallel to said flanges and stiffening the central portion of the buffing face and transferring buffing shocks to the resilient means, and follower lugs secured to said rearwardly directed flanges for transferring draft forces from said flanges to the resilient means.

4. A spring bumper and draft device for a vehicle comprising in combination, a transverse housing secured to the vehicle and having an opening directed outward toward the end of the vehicle, a combined bumper and draft member slidable longitudinally of the vehicle and enclosed in part by said housing, said member consisting in part of a buffing face and rearwardly directed flanges, at least one of which is provided with coupler receiving means, anchor means carried by said end housing and retaining said member within the housing, follower lugs secured to said rearwardly directed flanges, a rear follower normally engaging said lugs, a front follower normally engaging said anchor means, resilient means urging said followers apart, bumper reinforcing means stiffening the buffing face and transferring buffing shocks to the front follower independently of said anchor means during inward movement of the bumper, and a back stop carried by said end housing to prevent inward movement of the rear follower.

5. A spring bumper and draft device for a vehicle comprising in combination, a transverse housing secured to the vehicle and having an opening directed outward toward the end of the vehicle, a combined bumper and draft member slidable longitudinally of the vehicle and enclosed in part by said housing, said member consisting in part of a buffing face and rearwardly directed flanges, at least one of which is provided with coupler receiving means, anchor means carried by said end housing and retaining said member within the housing, follower lugs secured to said rearwardly directed flanges, a rear follower normally engaging said lugs, a front follower normally engaging said anchor means, resilient means urging said followers apart, bumper reinforcing means stiffening the buffing face and transferring buffing shocks to the front follower during inward movement of the bumper, and a back stop carried by said end housing to prevent inward movement of the rear follower, said back stop being interposed between said follower lugs and being operative to guide the bumper during its sliding movements.

6. A spring bumper and draft device for a vehicle comprising in combination, a transverse housing secured to the vehicle and having an opening directed outward toward the end of the vehicle, a combined bumper and draft member slidable longitudinally of the vehicle and enclosed in part by said housing, said member consisting in part of a buffing face and rearwardly directed flanges, at least one of which is provided with coupler receiving means, anchor means carried by said end housing and retaining said member within the housing, follower lugs secured to said rearwardly directed flanges, a rear follower normally engaging said lugs, a front follower normally engaging said anchor means and retained against outward movement thereby but independently thereof, and resilient means urging said followers apart, said follower lugs carrying said rear follower forward to compress the resilient

means during outward movement of the bumper member under draft forces.

7. A spring bumper and draft device for a vehicle comprising in combination, a housing arranged at the end portion of the vehicle and having upper and lower plates arranged in spaced relation, and a combined bumper and draft member slidably mounted in said housing, said bumper and draft member comprising a buffing face and rearwardly directed upper and lower flanges, at least one of said flanges being provided with coupler receiving means, a front follower within the bumper and draft member, a stationary element extending between the upper and lower plates and through the flanges of said bumper and draft member and against which the front follower is normally engaged, said stationary member constituting an abutment for limiting movement of said front follower in one direction, a rear follower, resilient means urging said followers apart, and means on said upper and lower flanges engaging the rear follower to move the latter longitudinally in the housing to compress the resilient means under draft forces.

8. A spring bumper and draft device for a vehicle comprising in combination, a transverse end housing secured to the vehicle and having an opening directed outward toward the end of the vehicle, a combined bumper and draft member slidable longitudinally of the vehicle and enclosed in part by said housing, said member consisting in part of a buffing face and rearwardly directed flanges, at least one of which is provided with coupler receiving means, a bolt extending across said end housing for retaining said bumper member within the housing, a front follower normally engaging said bolt, resilient means urging said follower against the bolt, means carried by said end housing providing a seat for said resilient means, and bumper reinforcing means extending substantially parallel to said flanges and engaging the central portion of said bumper face to stiffen the same and transfer buffing shocks to said front follower and resilient means independently of said bolt.

9. A combined spring bumper and draft unit comprising in combination, a bumper member having a web providing a bumping face and rearwardly directed flanges, follower lugs secured to said flanges, a rear follower engageable with said lugs, a front follower, resilient means urging said followers apart, and bumper reinforcing means engageable with the intermediate portions of said web and front follower, said bumper reinforcing means being secured to the front follower and free of attachment to said web.

10. A combined spring bumper and draft unit comprising in combination, a bumper member having a web providing a bumping face and rearwardly directed flanges, follower lugs secured to the rear edges of said flanges, a rear follower engageable with said lugs, a front follower, resilient means urging said followers apart, and bumper reinforcing means engageable with said web and front follower, an end housing having an outwardly directed opening defined in part by upper and lower flanges, said unit being insertable as a whole into said housing, and retaining means extending through said upper and lower flanges into engagement with the front follower to prevent outward movement thereof.

11. A combined spring bumper and draft unit comprising in combination, a bumper member having a web providing a bumping face and

rearwardly directed flanges, follower lugs secured to the rear edges of said flanges, a rear follower engageable with said lugs, a front follower, resilient means urging said followers apart, and bumper reinforcing means engageable with said web and front follower, an end housing having an outwardly directed opening defined in part by upper and lower flanges, a stop carried by said housing at the rear of the opening, said unit being insertable as a whole into said housing with the rear follower engaging the stop, and retaining means extending through said upper and lower flanges into engagement with the front follower to prevent outward movement thereof.

12. A combined spring bumper and draft unit comprising in combination, a bumper member having a web providing a bumping face and rear-

wardly directed flanges, follower lugs secured to said flanges, a rear follower engageable with said lugs, a front follower, resilient means urging said followers apart, bumper reinforcing means engageable with the intermediate portions of said web and front follower, said bumper reinforcing means being secured to the front follower and free of attachment to said web, an end housing having an outwardly directed opening defined in part by upper and lower flanges, a stop carried by said housing at the rear of the opening, said unit being insertable as a whole into said housing with the rear follower engaging the stop, and retaining means extending through said upper and lower flanges into engagement with the front follower to prevent outward movement thereof.

ROBERT C. KEPNER.
